(57) **CLAIM**

(21) Appl. No.: **29/319,641**

The ornamental design for the amphibious sport aircraft with
wing-fold, as shown and described.

(22) Filed: **Jun. 11, 2008**

DESCRIPTION

(51) **LOC (9) Cl.** 12-14

FIG. 1 is a front perspective view of an amphibious sport
aircraft showing our new design;

(52) **U.S. Cl.** D12/3; D12/4

FIG. 2 is a front elevation view of the amphibious sport
aircraft with wing fold;

(58) **Field of Classification Search** D12/319-345,

FIG. 3 is a rear elevation view of the amphibious sport aircraft
with wing fold;

D12/1, 2, 3, 4; 244/45 R, 23 R, 101, 106

FIG. 4 is a right side elevation view one side of the amphibi-
ous sport aircraft with wing fold;

See application file for complete search history.
